UNITED STATES PATENT OFFICE.

EDWARD B. ALLEN, OF BRIDGEPORT, CONNECTICUT, ASSIGNOR TO THE SINGER MANUFACTURING COMPANY, A CORPORATION OF NEW JERSEY.

BUTTONHOLE-SEWING MACHINE.

1,344,748.

Specification of Letters Patent. Patented June 29, 1920.

Application filed July 26, 1915. Serial No. 41,884.

To all whom it may concern:

Be it known that I, EDWARD B. ALLEN, a citizen of the United States, residing at Bridgeport, in the county of Fairfield and State of Connecticut, have invented certain new and useful Improvements in Button-hole-Sewing Machines, of which the following is a specification, reference being had therein to the accompanying drawings.

This invention relates especially to an improvement in that class of buttonhole sewing machines in which the clamping elements of the work-holder are automatically operated to close upon the work and are spread laterally for stretching it after the slit is cut and preparatory to the stitching upon completion of which the clamp is unspread and opened for release of the work preparatory to the succeeding button-hole-producing operation. It has for its particular object the provision of simple and effective means to insure the prompt opening and unspreading of the work-holder at the completion of the stitching operation.

The present invention is preferably embodied in a machine of the type represented in my pending application Serial No. 872,333, filed November 16, 1914, and comprising a cutter-actuating shaft driven independently of the actuating means for the stitch-forming mechanism through periodical connection with and disconnection from an actuating belt-wheel which is continuously driven. According to said application, the slit-cutting elements are carried by cutter-levers mounted upon a traveling fulcrum and derive their operative movements from suitable cams upon the cutter-shaft.

The work-holder comprises traveling clamp-plates mounted for slight movement toward and from each other and sustaining upper clamping levers carrying clamping feet adapted to coöperate with them in gripping the work, the clamping levers being depressed by cam projections upon connected sections of a cam-shaft one of which carries a tappet-arm adapted for engagement by a clamp-closing rock-lever actuated by a cam upon the cutter-shaft. As in my Patent No. 1,240,642, of Sept. 18,

1917, the spreading of the separable pairs of clamping members of the work-holder is preferably effected by the movement of the traveling support for the cutter-lever 55 fulcrum-pin.

In the preferred embodiment of the present invention, one section of the cam-shaft of the work-holder carries a second tappet-arm adapted for engagement to effect the 60 opening of the work-holder by a tripping pin carried by a sliding support which is connected with a reciprocating bar carrying a spring-pressed angular coupling lever. One arm of the coupling lever is formed 65 with a notch adapted to embrace a pin upon an arm of a vibrating angle-lever having a second arm carrying a roller-stud which enters a cam-groove in the actuating belt-wheel to which the cam-shaft is adapted to 70 be connected in operating the cutting device. The other arm of the coupling lever is adapted for engagement by a detent-lever having a portion lying in the range of movement of a reciprocating plunger of the stop-motion which controls the period of action 75 of the stitch-forming mechanism.

The tripping pin support is normally inactive, and derives an operative reciprocating movement through the coupling of 80 the connected bar with the constantly vibrating lever; and this is effected through the tripping of the detent-lever by the rise of the stop-motion plunger in stopping the stitch-forming mechanism which causes the 85 bar, and with it the coupling lever, to move forwardly, and on return of the coupling lever the engagement of the latter with the detent-lever for effecting the uncoupling of the temporarily connected parts. 90

As shown and described in my said Patent No. 1,240,642, the clamp-spreading device is maintained in spreading position by means of a latch-lever which according to the present improvement is adapted for 95 engagement and retraction by the sliding support for the tripping pin before referred to for effecting the unspreading of the work-holder through the action of a suitable spring. The unspreading of the work-holder is effected by the same means which effects the opening of the work-holder, both 100

of these actions being produced by an element of the slit-cutting mechanism under control of the stop-motion, but independently of the stitch-forming and feeding mechanisms.

The invention will be understood by reference to the accompanying drawings, in which Figure 1 is a front side elevation of a buttonhole sewing machine embodying the invention, and Fig. 2 a plan of the same with the bracket-arm removed to expose the parts beneath. Fig. 3 is a bottom view of the main slide-plate of the work-holder and a portion of the clamp-spreading means, and Fig. 4 is a detail sectional elevation of the same. Fig. 5 is a side elevation and Fig. 6 a rear end elevation of the clamp-opening mechanism. Fig. 7 is a detail elevation of the coupling lever. Fig. 8 is a transverse section showing one pair of the work-holder spreading elements.

As represented in the drawings, the frame of the machine comprises the hollow rectangular base 1 sustaining the bracket-arm comprising the hollow standard 2 and lateral arm 3 terminating in the hollow head 4. Journaled within the base is the main shaft 5 formed with the cranks 6 which are connected by the pitmen 7 with similar cranks 8 of the upper shaft 9 journaled in the arm 3.

The stitch-forming mechanism is constructed substantially in accordance with my Patent No. 1,030,046, of June 18, 1912, the needle mechanism being that of my Patent No. 1,161,277, of November 23, 1915. The needle 10 is carried by the laterally jogging needle-clamp 11 sustained upon the lower end of the vertically reciprocating needle bar 12 which is in practice journaled for rotation in the head 4. The needle-bar has fixed thereon the collar 13 carrying the lateral stud 14 which is embraced by one end of the pitman 15 whose opposite end embraces the crank-pin 16 upon the crank-disk 17 carried by the actuating shaft 18. This shaft is driven by the shaft 9 through a trammel connection comprising the disks 19 and 20 mounted upon the respective shafts and provided with the usual pin and cross-groove connection through which the shaft 18 derives two rotations for each rotation of the shaft 9. The needle 10 is adapted to cooperate with the usual looper mechanism located below the work and operatively connected with the mainshaft 5, as shown and described in my said Patent No. 1,030,046.

As shown and described more fully in my reissued Patent No. 14,529, of October 8, 1918, the main-shaft 5 has a driving connection, including the intermeshing bevel pinions 21 and 22 and the intermittently moving gear-wheel 23 with the feed-wheel 24 which has usual or suitable connections with the longitudinally moving slide-plate 25 and the cross slide-plate 26 mounted thereon.

Upon the cross slide-plate are pivotally mounted by means of studs 27 the usual clamp-plates 27 provided with the lower work-supporting plates 28 upon which the work is clamped by the feet 29 pivotally secured upon the forward ends of the clamp-arms 30 which are fulcrumed at their opposite ends within the brackets 31 secured upon the clamp-plates 27. The clamp-plates are drawn together by means of the springs 32 having their opposite ends connected respectively with the studs 33 sustained by the clamp-plates and the studs 34 upon projecting lugs of the cross slide-plates; and the clamp-arms 30 are pressed normally upward by means of springs 35 interposed between them and the clamp-plates 27.

Journalized in the bearing blocks 31 are the aligned sections 36 of the clamp-operating rock-shaft, each section being provided upon the lower side with the cam projection 37 adapted for engagement with the wearing plate 38 of its respective clamp-arm 30. The rock-shaft sections are provided upon their adjacent ends with the interlocking crank-arms 39 and 40, and that at the front side of the machine has in addition the angularly disposed tappet-arms 41 and 42 and the finger-lever 43 by means of which the rock-shaft may be turned to depress and release the clamp arms.

Suitably journalized at the rear of and above the top of the base 1 is the transverse cutter-shaft 44 carrying upon its forward end the continuously driven belt-wheel 45 embraced by the driving belt 46. As set forth more fully in my Patent No. 1,048,786, of Dec. 31, 1912, the belt-wheel 45 has the annular rib 47 provided with notches 48 adapted to be entered by the coupling lug 49 upon the slide-block 50 which is fitted within a suitable radial guideway of the disk 51 having its hub 52 secured upon the cutter-shaft, the slide-block 50 being normally pressed outwardly by a spring and maintained in inner inoperative position by engagement of a stud 53 thereon with a cam element 54 upon the controlling lever 55 fulcrumed at 56 upon the bed 1. This coupling device is so constructed that the cutter-shaft is uncoupled from the belt-wheel 45 at the completion of a rotation of the latter.

The connection, therefore, between the cutter operating and clamp closing shaft 44 and the continuously running actuator or belt-wheel 45 is of a one-to-one nature; that is, the shaft 44 is driven through one complete revolution or cycle of motion during the time the actuator 45 performs one complete revolution or cycle of motion. This is an important advantage from the standpoint of high speed operation and is superior to worm and wheel or other speed reducing connections requiring the actuator to per-

form a plurality of revolutions in order to drive the cutter mechanism through a cycle of operations.

The cutter-shaft is provided with the cutter-actuating cams 57 and 58 adapted for engagement with the rearward ends of the upper and lower cutter-levers 59 and 60, respectively, carrying the buttonhole cutting elements 61 and 62. The cutter-levers are mounted intermediate their ends upon the fulcrum-pin 63 which is sustained by the slide-block or support 64 pivotally attached by means of the stud-pin 65 with the connecting rod 66 carrying the roller-stud 67 entering the cam-groove 68 of the cam-wheel 69 fixed upon the cutter-shaft 44. By the means just described, in the rotation of the cutter-shaft the cutting elements are advanced into register with the needle-opening of the work-holder and closed upon the work and then returned into retracted position in a manner well known.

The cutter-shaft carries a clamp-closing cam 70 adapted for engagement with the rearwardly extending arm of the rock-lever 71 having its hub 72 fulcrumed upon the fixed stud 73 and provided with a forwardly extending arm adapted for engagement with the tappet-arm 41 of the clamp-operating rock-shaft 36. The rock-lever 71 is normally maintained in operative contact with the cam 70 by means of the spring 74. The lateral tappet-arm 41 is in its upper position when the clamp is open preparatory to a buttonhole producing operation, and the tilting of the rock-lever 71 just prior to the closing of the buttonhole cutting elements under the action of the cutter-shaft effects the depression of such tappet-arm to turn the rock-shaft 36 and depress the clamp arms.

When the clamp is closed, as represented in Fig. 1, the upwardly extending tappet-arm 42 is in backwardly inclined position within the range of movement of the extremity of the trip-rod 75 having its threaded rearward portion adjustably secured by means of the clamp-nuts 76 within the apertured boss 77 of the post 78 with its foot 79 secured upon the slide-bar 80 which is in practice fitted within a suitable guideway formed in the top of the base 1, as shown in my said application Serial No. 872,333. The post 78 has upon its rearward edge the lug 81 carrying the screw-stud 82 which is embraced by the apertured lateral boss 83 at one end of a reciprocatory bar 84 which is provided near its other end with the longitudinal slot 85 entered by the fixed supporting stud-pin 86 projecting from the frame-standard 2. The bar 84 is normally drawn backward by a spring 84^x.

Pivottally mounted upon the rearward end of the bar 84 by means of the stud-screw 87 is an angular coupling lever formed with the forwardly extending arm 88 and the de-

pending arm 89. The arm 88 is formed with a wedge-shaped forward end portion adjacent which is the notch or recess 90 in the lower edge. The arm 88 has upon one of its side faces the stud-screw 91 entering and resting upon the bottom of a notch 92 in the upper edge of the bar 84 upon which it is normally pressed by the forwardly extending arm of a spring 93 secured upon said bar by the fastening screw 94.

The notch 90 of the coupling lever arm 88 is adapted to embrace a roller-stud 95 upon the upright arm 96 having its hub 97 fixed upon the rock-shaft 98 which is journaled in the front side wall of the base 1. The rock-shaft 98 has fixed upon its outer end the hub 99 of a lateral arm 100 carrying a roller-stud 101 which enters an oval cam-groove 102 formed in the inner face of the belt-wheel 45. The arms 96 and 100 with the supporting rock-shaft 98 constitute a constantly vibrating angle-lever adapted to impart to the bar 84, and hence to the trip-rod 75, to-and-fro movements when the notched lateral arm of the coupling lever is in engagement with the roller-stud 95. It will be noted that the connection between the clamp-opening and unspreading bar 84 and the actuator 45 is of a one-to-one nature, resulting in the performance of one complete cycle of motion by the bar 84 during one revolution of the actuator 45, with advantages similar to those described in connection with the buttonhole cutting and clamp-closing mechanisms.

The rearwardly notched lower extremity of the coupling lever arm 89 is adapted to normally engage the forward face of the upright-arm 103 of an angular detent-lever fulcrumed upon the stud-screw 104 tapped into the base 1 and provided with a lateral arm 105 extending beneath the stud-screw 106 and normally pressed downwardly under the action of the spring 107 having one extremity engaging the arm 105 of the detent-lever and the other extremity attached to the screw 106.

Extending beneath the arm 105 is a trip-arm 108 rigidly secured by means of the screw 109 upon the block 110 which is slidably sustained by the stop-motion lever 111 and provided with the lateral tooth 112. The stop-lever 111 is fixed upon the rock-shaft 113 and is provided with a lateral projection 114 between which and the standard 2 is interposed the spring 115 by means of which the lever is thrown into a stopping position wherein the tooth 112 is caused to rest upon the eccentric periphery of the disk 116 of the clutch for coupling the main-shaft with the constantly running belt-wheel 117 driven by the belt 118. The stop-motion is constructed and operated substantially as described in my Patent No. 1,024,490, of April 30, 1912.

At the completion of a buttonhole-producing cycle of operation of the machine, the bar 84 is in extreme retracted position, the coupling lever-arm 89 being in engagement with the detent-lever arm 103, and the coupling lever arm 88 being raised out of operative relation with the constantly reciprocating roller-stud 95 of the vibratory lever 96. Upon the rise of the block 110 under the action of the cam portion of the ring 116 upon the tooth 112, the trip-arm rises and tilts the detent-lever for disengagement of its arm 103 from the coupling lever which latter descends under the action 15 of its spring and engages the roller-stud 95 at the end of its next reciprocation. As thus coupled with the vibratory lever 96, the bar 84 moves forward and carries the trip-rod 75 into operative engagement with 20 the tappet-arm 42 whereby the clamp is opened.

The trip-arm 108 having descended with the tooth 112 when entering the peripheral notch of the clutch-disk 116 to stop the 25 stitch-forming mechanism, and the detent-lever having thus been permitted to return to initial operative position under the action of its spring 107, the return movement of the bar 84 causes the reengagement of the 30 coupling lever-arm 89 with the detent lever-arm 103 whereby the coupling lever-arm 88 is raised into retracted position and the bar 84 thereby uncoupled from the vibratory lever 96 at the completion of a single operative reciprocation. In the accompanying 35 drawings, the machine is represented at the completion of a stitching period, the stop-motion having operated to arrest the main-shaft 5 and the coupling lever having immediately assumed operative relation with the vibratory lever 96 in readiness for its operative or clamp-opening movement.

The cross slide-plate 26 has formed in its upper face a U-shaped slideway extending 45 toward the front end in which is fitted a correspondingly shaped slide-plate 119 carrying upon the upper face of each of its lateral members a cam-block 120. The outer cam-edge of each of the blocks 120 is 50 adapted to engage the depending stud 121 upon a block 122 which is adjustably secured by means of screws 123 upon a suitable transverse seat of each clamp-plate 27. The cross-member of the slide-plate 119 has at 55 its inner edge a substantially circular recess within which is fitted the correspondingly shaped end of a link 124 whose similar opposite end is fitted within a correspondingly shaped recess in a crank-arm 125 upon the 60 upper end of a rocking pin 126. The rocking of the pin 126, through the described connections, causes the to-and-fro movement of the slide-plate 119 and the consequent operative engagement of the studs 121 with 65 the cam-blocks 120 to cause the reciprocal

recession and approach of the clamp-plates 27 in opposition to and under the action of their respective springs 32.

The mechanism for rocking the pin 126 to spread and unspread the work-clamping elements is similar in general construction to that shown and described in my said Patent No. 1,240,642. The pin 126, which is journaled in an aperture of the cross slide-plate 26, has fixed upon its lower end the hub 127 of the lateral arm 128 attached to one end of the spring 129 whose opposite end is attached to a stud 130 upon the plate 26. The hub 127 is provided also with the oppositely extending rigid arms 131 and 132 disposed at substantially right angles with the arm 128.

The outer extremity of the arm 131 lies within the range of movement of the reciprocating cam-block 133 pivotally mounted by means of the stud-screw 134 upon the head 135 of a rack-bar 136 meshing with the pinion 137 which is mounted upon the fixed stud 138 and meshes in turn with a series of rack-teeth 139 upon the adjacent edge of the traveling fulcrum-block 64 of the slit-cutting mechanism. The body of the cam-block 133 has its upper face formed at the outer extremity with a bevel, and a lateral extension 133^x thereof has an abrupt shoulder adapted for engagement with the edge of the arm 131, the cam-block being maintained yieldingly within the plane of movement of the arm 131 by means of the spring 140.

Journaled upon the stud-screw 141 upon the under face of the slide-plate 26 is a plural-armed latch-lever comprising an arm 142 notched in its outer end to form a detaining shoulder for the arm 132, a second annularly arranged arm 143 having a lateral finger 144 with beveled extremity for engagement with the beveled face of the cam-block 133, a third arm 145 projecting within the range of movement of the end of the slide-bar 80, and a fourth arm 146 having connected therewith one end of a spring 147 whose other end is attached to a stud 148 depending from the slide-plate 26. The clamp-spreading motion of the lever 128, 132, under the influence of the spring 129, is arrested by the stop-pin 149.

In the advance of the cutting device, comprising the cutter-levers with their cutting elements and the traveling fulcrum, into 120 cutting position, the rack-bar 136 recedes from advance position and the cam-block 133 is depressed by engagement of the beveled faces of the extension 133^x and the arm 131; and in the retraction of the cutting device after a cutting operation, the rack-bar 136 advances and effects the engagement of the abrupt shoulders 133^x and 131, thereby turning the pin 126 and through its crank-and-link connection with 125 130

the slide-plate 119 effecting the simultaneous engagement of the cam-blocks 120 with their respective pins 121 to spread the clamps. The extremity of the arm 132, having previously rested against the adjacent edge of the latch lever arm 142, is moved along the same in the turning of the pin 126 until it comes into register with the notch of the latch-arm, when the latter under the action of the spring 147, snaps into locking engagement therewith which it maintains during the succeeding stitching operation.

In the advance of the slide-bar 80 with its tripping pin 75 to open the work-clamp, its forward extremity engages the arm 145 of the latch-lever and turns the latter to disengage the latch-arm 142 from the arm 132. At the same time the wedge-shaped extremity of the finger 144 thrusts the cam-block 133 downwardly to permit the arm 131 to assume normal unspredding position under the action of the spring 129, the turning of the crank-arm 125 thus causing the return shift of the plate 119 to interrupt the forcible engagement of the cam-blocks 120 with the studs 121 so as to permit the separable clamping members to come together under the action of their respective springs 32.

30 The actuator for the buttonhole-cutting and clamp-operating devices consists, in the present embodiment of the invention, of the constantly running wheel 45 which performs repeated excursions from any given position during each buttonhole producing cycle; but it is evident that the specific nature of this element is not material to the present invention in certain of its aspects, so long as it performs its necessary function 40 in connection with the movement of the parts which depend upon it for their operation.

It will be observed that in the machine represented in the drawings, the opening, closing, spreading and unspredding of the work-holder are effected by connections with the slit-cutting mechanism which is driven independently of the stitch-forming and feeding mechanisms, and that the closing and opening of the work-holder are effected through one-to-one operating connections with the actuating means for the cutting device, these connections being respectively with the constantly driven belt-pulley 50 or driving member 45 and the cam upon the cutter-shaft or driven member 44 of the actuating means. As set forth in my said Patent No. 1,240,642, a connection is provided between the cam-wheel 69 and the stop-lever 55 60 for tilting the latter to inaugurate the stitching operation succeeding a slit-cutting operation, the tripping of the stop-motion being effected by a suitable connection with the feed-wheel 24.

65 This machine is of the type designed for

working upon firm material such as leather in which it is customary to cut the button-hole slit preparatory to the edge stitching operation; but it is obvious that the present improvement is equally adapted to machines 70 designed especially for operation upon cloth wherein the slit-cutting operation usually succeeds the stitching operation. In either case the reciprocating parts connected with the cutting mechanism are employed to perform initial and final actuations of the 75 clamp-operating and spreading devices; and the timing of operation of the cutting device in relation to that of the stitch-forming and feeding mechanisms will determine the 80 manner of connecting these reciprocating actuating parts with the parts which they are required to actuate.

It is evident that the present improvement is susceptible of considerable modification 85 within the scope of the present invention and that certain of its features are capable of use separately from others.

Having thus set forth the nature of the invention, what I claim herein is:—

1. In a buttonhole sewing machine, in combination, stitch-forming and feeding mechanisms, a work-clamp, clamp-opening means, a slit cutting device, an actuator operative independently of the stitch-forming 90 and feeding mechanisms, and independently acting means for establishing a one-to-one operative connection of the clamp-opening means and the cutting device respectively with said actuator.

2. In a buttonhole sewing machine, in combination, stitch-forming mechanism, actuating means therefor, a work-clamp, clamp-opening means, a continuously rotating actuator performing repeated idle 95 excursions for each buttonhole producing cycle and operative independently of the stitch-forming mechanism and its actuating means, means for establishing operative connection between said actuator and the 100 clamp-opening means, and means for interrupting said operative connection at the completion of the first working cycle of motion of said actuator.

3. In a buttonhole sewing machine, in 110 combination, stitch-forming mechanism, a shaft for actuating the same, a stop-motion for controlling its period of action, a work-clamp, clamp-opening means, an actuator operable independently of said shaft during 115 stitching periods, and means controlled by the stop-motion for establishing operative connection between said actuator and the clamp-opening means substantially at the time the stitch-forming mechanism is being 120 stopped.

4. In a buttonhole sewing machine, in combination, stitch-forming mechanism, a stop-motion for controlling its period of action, a work-clamp, clamp-opening means, 125

an actuator, means controlled by the stop-motion for establishing operative connection between said actuator and the clamp-opening means as the stitch-forming mechanism is being stopped, and means acting independently of the stop-motion for interrupting said connection.

5. In a buttonhole sewing machine, in combination, stitch-forming and feeding mechanisms, a work-clamp, clamp-opening and closing means, a slit-cutting device, operating means therefor independent of the stitch-forming and feeding mechanisms, and operative connections between said operating means and the clamp-opening and closing means, respectively; the operative connections for the clamp-closing means including a normally stationary element of the slit-cutting device.

10. In a buttonhole sewing machine, in combination, stitch-forming and feeding mechanisms, a stop-motion for determining their period of coöperative action, a work-clamp, clamp-opening and closing means, slit-cutting mechanism, an operative connection between the clamp-closing means and the slit-cutting mechanism for closing the clamp during the action of the slit-cutting mechanism, and means controlled by 25 the stop-motion for establishing operative connection between the clamp-opening means and the cutting mechanism.

15. In a buttonhole sewing machine, in combination, a work-clamp, clamp-opening means, a slit-cutting device, an actuator from which the clamp-opening means and cutting device are normally disconnected, and means for establishing a one-to-one operative connection of the slit-cutting device 30 and the clamp-opening means with said actuator.

20. In a buttonhole sewing machine, in combination, a work-clamp, normally inactive clamp-closing means, an element performing repeated reciprocations during a buttonhole producing cycle, means for coupling the clamp-opening means with said reciprocating element, and means for effecting the uncoupling of said means and element at the completion of the first working reciprocation of said element.

25. In a buttonhole sewing machine, in combination, stitch-forming mechanism, a stop-motion for controlling its period of action, a work-clamp, normally inactive clamp-opening means, a reciprocating element operative while the stitch-forming mechanism is at rest, and means controlled by said stop-motion for coupling the clamp-opening means with said reciprocating element.

30. In a buttonhole sewing machine, in combination, stitch-forming mechanism, a stop-motion for controlling its period of action, a work-clamp, normally inactive

clamp-opening means, a reciprocating element, means controlled by said stop-motion for coupling the clamp-opening means with said reciprocating element, and means for uncoupling said parts.

70

11. In a buttonhole sewing machine, in combination, a work-clamp, normally inactive clamp-opening means, a reciprocating element performing repeated excursions during a buttonhole-producing cycle, a rotary element from which the latter derives at regular intervals its reciprocatory movements, and means for coupling the clamp-opening means with said reciprocating element.

75

12. In a buttonhole sewing machine, in combination, stitch-forming mechanism, a work-clamp, normally inactive clamp-opening means, a slit-cutting device, a continuously driven cam-wheel operative independently of the stitch-forming mechanism, a vibratory lever deriving from said cam-wheel uniformly recurring operative movements, means whereby the cutting device is connected with and disconnected from said cam-wheel, and means whereby the clamp-opening means is coupled to and uncoupled from said vibratory lever.

80

13. In a buttonhole sewing machine, in combination, a work-clamp, normally inactive clamp-opening means including a reciprocatory bar, a continuously driven cam-wheel, a reciprocating element deriving from said cam-wheel uniformly recurring operative movements, a normally retracted coupling element mounted upon said reciprocatory bar, and means for effecting the operative connection of the coupling element with said reciprocating element.

85

14. In a buttonhole sewing machine, in combination, stitch-forming mechanism, a stop-motion therefor, a work-clamp, normally inactive clamp-opening means including a reciprocatory bar, a continuously driven cam-wheel, a reciprocating element deriving from said cam-wheel uniformly recurring operative movements, a normally retracted coupling element mounted upon said reciprocatory bar, and means controlled by said stop-motion for effecting the operative connection of the coupling element with said reciprocating element.

90

15. In a buttonhole sewing machine, in combination, stitch-forming mechanism, a stop-motion therefor, a work-clamp comprising upper clamp-levers and a cam-shaft provided with a tappet-arm and having an operative connection with said clamp-levers, a tripping element adapted for engagement with said tappet-arm, a movable support therefor, an endwise movable bar connected with said support, a spring-pressed coupling lever mounted thereon, a continuously driven cam-wheel operative independently of the stitch-forming mechanism, a vibratory lever

115

120

125

130

deriving from said cam-wheel uniformly recurring operative movements, and means controlled by said stop-motion for effecting the engagement of the coupling lever with 5 said vibratory lever.

16. In a buttonhole sewing machine, in combination, stitch-forming mechanism, a stop-motion therefor, a work-clamp comprising upper clamp-levers and a cam-shaft 10 provided with a tappet-arm and having an operative connection with said clamp-levers, a tripping element adapted for engagement with said tappet-arm, a movable support therefor, an endwise movable bar connected 15 with said support, a spring-pressed coupling lever mounted thereon, a continuously driven cam-wheel operative independently of the stitch-forming mechanism, a vibratory lever deriving from said cam-wheel 20 uniformly recurring operative movements, means controlled by said stop-motion for effecting the engagement of the coupling lever with said vibratory lever, and means for insuring the retraction of the coupling lever 25 in the same rotation of said cam-wheel.

17. In a buttonhole sewing machine, in combination, stitch-forming mechanism, a stop-motion including a cam-wheel and a reciprocating plunger operatively connected 30 therewith, a work-clamp, normally inactive clamp-opening means including a movable element, a normally retracted coupling element supported thereby, a reciprocatory element with means for imparting to it uniformly recurring operative movements, and 35 a detent-lever engaging and normally maintaining the coupling element in retracted position and having an arm extending within the range of movement of the reciprocating plunger of said stop-motion.

18. In a buttonhole sewing machine, in combination, a work-clamp, clamp-opening and closing means, a slit-cutting device, a rotary cam-shaft with which the same is operatively connected, a continuously driven 45 actuating wheel, coupling means whereby said cam-shaft is connected with and disconnected from said wheel in a single rotation of the latter, an operative connection between said cam-shaft and the clamp-closing means, and means for establishing operative connection between the clamp-opening 50 means and said rotary actuating wheel.

19. In a buttonhole sewing machine, in combination, a work-clamp, spreading means therefor, slit-cutting mechanism, a continuously rotating actuator, coupling means for connecting the cutting mechanism 55 with said actuator, a connection between the cutting mechanism and said spreading means for effecting the spreading of the clamp, and means for connecting the spreading means with said actuator for unspre- 60 wing the clamp.

65 20. In a buttonhole sewing machine, in

combination, a work-clamp, spreading means therefor, slit-cutting mechanism, an actuator therefor, a coupling for temporarily connecting the cutting mechanism with said actuator, and means adapted for operative connection with said actuator respectively through and independently of said cutting mechanism whereby the spreading means are reciprocally operated to effect the spreading and unspre- 70 wing of the clamp. 75

21. In a buttonhole sewing machine, in combination, a work-clamp, opening and closing and spreading means therefor, slit-cutting mechanism, a continuously running actuator for said slit-cutting mechanism, 80 operative connections between the slit-cutting mechanism and the closing and spreading means for effecting closing and spreading of the work-clamp, and operative connections between said actuator and the 85 clamp opening and spreading means for effecting the opening and unspre- wing of the work-clamp.

22. In a buttonhole sewing machine, in combination, a work-clamp, opening and closing and spreading means therefor, slit-cutting mechanism, a constantly running actuator therefor, an automatic throw-out clutch between said slit-cutting mechanism and said actuator, operative connections between a driven element of the slit-cutting mechanism and the clamp-closing and spreading means for effecting the closing and spreading of the clamp, and operative connections between said actuator and the 100 clamp-opening and spreading means for effecting the opening and unspre- wing of the clamp. 95

23. In a buttonhole sewing machine, in combination, a work-clamp, spreading 105 means therefor, slit-cutting mechanism, and independent operative connections between the slit-cutting mechanism and the spreading means whereby the clamp is successively spread and unspre- 110 wing.

24. In a buttonhole sewing machine, in combination, a work-clamp, spreading means therefor, a slit-cutting device, actuating means therefor including driving and driven elements with a coupling for establishing and interrupting operative relation between them, an operative connection between said driven element and the spreading means for effecting the spreading of the work-clamp, and a connection between said 115 driving element and the spreading means for effecting the unspre- wing of the work-clamp. 120

In testimony whereof I have signed my name to this specification in the presence of 125 two subscribing witnesses.

EDWARD B. ALLEN.
